TUBE CUTTER

Sidney J. Shames, 57 Holly Place, Briarcliff Manor, N.Y.
10510, and Harold Shames, 5 Agnes Circle, Ardsley,
N.Y. 10502

Filed Sept. 5, 1969, Ser. No. 19,038

Term of patent 14 years

Int. Cl. D8—02

U.S. Cl. D8—60

FIG. 1 is a perspective view of a tube cutter embodying our new design;

FIG. 2 is a side elevational view of the same;

FIG. 3 is an end view of the same taken looking from the right of FIG. 2;

FIG. 4 is an edge view of the same taken looking downward from above FIG. 2, and fragmentarily shown for convenience of illustration;

FIG. 5 is another edge view of the same taken looking upwardly from below FIG. 2;

FIG. 6 is another end view of the same taken looking from the left of FIG. 2; and

FIG. 7 is an elevational view of the same taken looking from the left of FIG. 6, and fragmentarily shown for convenience of illustration.

We claim:

The ornamental design for a tube cutter, as shown and described.
